FIRE EXTINGUISHER

James Knox Lumbar, La Junta, Colo.

Application March 11, 1944, Serial No. 526,034

2 Claims. (Cl. 169—29)

This invention relates to new and useful improvements in fire extinguishers.

The principal object of the present invention is to provide a fire extinguisher which will act instantaneously at a certain temperature to discharge a fine spray of a fire smothering substance, such as carbon tetrachloride.

Another important object of the invention is to provide a fire extinguisher unit for installation in high pressure extinguishing systems employing a chemical fire extinguishing fluid, which in operation will serve to vent the high pressure line at a point of high pressure in a quick and effective manner.

These and other important objects and advantages of the invention will become apparent to the reader of the following description.

In the drawing—

Figure 1 represents a front elevational view of the extinguisher.

Figure 2 is a side elevational view.

Figure 3 is a fragmentary vertical sectional view through the lower portion of the extinguisher.

Figure 4 is a section on the line 4—4 of Figure 1.

Referring to the drawing wherein like numerals designate like parts, it can be seen that the unit is to be installed in a high pressure pipe line containing carbon tetrachloride under pressure and in this conjunction a threaded T-fitting 5 is interposed in the pipe line (not shown), this fitting having a depending threaded portion *a* which is threaded disposed downwardly through an opening in a cover plate 6 which is secured to a shell 7 forming part of the present invention, the cover being secured in place by machine screws 8.

The lower portion of the shell 7 is grooved as at 9, the lower flange portion 10 being interrupted by slots 11 through which lugs 12 on the upper end of a glass bowl 13 can be disposed after which the bowl is rotated to properly support the bowl in place, and as can be seen in Figure 3, a suitable gasket 14 is provided. However, it is to be understood that other means for securing the bowl 13 in place may be provided.

The inside of the shell 7 has an inwardly disposed shoulder 15 from which depends a tube 16, the same being open at its lower end. In the lower end portion of the tube 16 is a spider 17 from which a leg 18 depends and supports a chemical spreader 19, the peripheral portion of this spreader being beveled and being in close spaced relation with the lower end of the tube 16.

This device has a hammer for breaking the

bowl 13 and this consists of a swingable arm 20 provided with a head 21 at its free end. The arm 20 is pivoted as at 22 on the cover 6 and a spring 23 is employed for driving the arm downwardly, when released, in order that the head 21 will strike and break the bowl 13.

An apertured ear 24 is provided on the arm 20 adjacent the head 21, and an eye 25 is secured as at 26 on the cover 6. Here it will be noted that numeral 27 is a fusible link connecting the ear 24 with the eye 25 and wires 28 and 29 may extend therefrom to suitable indicating or alarm means for warning inhabitants of a building or home that a particular extinguishing unit has operated. The link 27 may be of any suitable material and set to melt at approximately 165° Fahrenheit.

It can now be seen, that when the element 27 fuses, the arm 20 will be released and the head 21 in being carried downwardly in response to the force of the spring 23 will strike and break the bowl 13, thus liberating the carbon tetrachloride, which in passing between the lower end of the tube 16 and the spreader 19 will emanate in a fine mist, covering and smothering the adjacent fire.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

- 35 1. A fire extinguisher comprising a hollow body, a fragile bowl depending from the body, said bowl containing a fire extinguishing fluid, a tube depending from said body into the bowl, and a disc depending from said tube and forming together with the lower end of the tube a spreader enclosed by said bowl, and heat responsive means for breaking the fragile bowl.
- 40 2. A fire extinguisher comprising a hollow body, a fragile bowl depending from the body, said bowl containing a fire extinguishing fluid, and heat responsive means for breaking the fragile bowl, said means for breaking the bowl consisting of a swingable arm having a head, spring means for forcing the arm and head to break the bowl and a fusible element for holding the arm and head in normal position, said body having a tube depending into the bowl and a fluid spreader in closely spaced relation from the bottom of the tube and enclosed by the bowl.

JAMES KNOX LUMBAR.
